US00D909818S

(12) United States Design Patent (10) Patent No.: US D909,818 S
 Hunter et al. (45) Date of Patent:  Feb. 9, 2021

(54) MUG	2,128,466 A	8/1938	Machotka
(71) Applicant: YETI Coolers, LLC , Austin, TX (US)	2,215,402 A	9/1940	McDonald
(72) Inventors: Desiree Hunter , Austin, TX (US); Robert Throop , Austin, TX (US); Mark Carlson Rane , Austin, TX (US); Laura Flores , Austin, TX (US); Michael Cieszko , Austin, TX (US)	2,215,691 A	9/1940	East
	2,378,867 A	6/1945	Reichart
	2,414,697 A	1/1947	Pettersson
	2,484,608 A	10/1949	Cheyney
	2,610,489 A *	9/1952	Clemensen .....
			A47G 19/2205
			215/374
(73) Assignee: YETI Coolers, LLC , Austin, TX (US)	2,675,954 A	4/1954	Vogel
() Term: 15 Years	D177,559 S	5/1956	Emmert
(21) Appl. No.: 29/658,902	2,871,051 A	1/1959	Nesslein et al.
(22) Filed: Aug. 3, 2018	D186,555 S	11/1959	Hunt
(51) LOC (13) Cl. 07-01	2,928,570 A	3/1960	Fitch
(52) U.S. Cl.	2,981,562 A	4/1961	Long
USPC D7/536; D7/533	3,118,560 A *	1/1964	Cornelius .....

CLAIM

The ornamental design for a mug, as shown and described.

DESCRIPTION

The file of this patent contains at least one drawing executed in color. Copies of this patent with color drawings will be provided by the Office upon request and payment.

FIG. 1 is a top, front, left perspective view of a mug showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a cross section view showing a section taken along line 8-8 of FIG. 6 thereof;

FIG. 9 is a top, front, left perspective view of a first alternative claimed configuration of the mug of FIGS. 1-8 showing our new design;
FIG. 10 is a front view thereof;
FIG. 11 is a rear view thereof;
FIG. 12 is a right side view thereof;
FIG. 13 is a left side view thereof;
FIG. 14 is a top view thereof;
FIG. 15 is a bottom view thereof;
FIG. 16 is a cross section view showing a section taken along line 16-16 of FIG. 14 thereof;
FIG. 17 is a top, front, left perspective view of a second alternative claimed configuration of the mug of FIGS. 1-8 showing our new design;
FIG. 18 is a front view thereof;
FIG. 19 is a rear view thereof;
FIG. 20 is a right side view thereof;
FIG. 21 is a left side view thereof;
FIG. 22 is a top view thereof;
FIG. 23 is a bottom view thereof;
FIG. 24 is a cross section view showing a section taken along line 24-24 of FIG. 22 thereof;
FIG. 25 is a top, front, left perspective view of a third alternative claimed configuration of the mug of FIGS. 1-8 showing our new design;
FIG. 26 is a front view thereof;

FIG. 27 is a rear view thereof;
FIG. 28 is a right side view thereof;
FIG. 29 is a left side view thereof;
FIG. 30 is a top view thereof;
FIG. 31 is a bottom view thereof;
FIG. 32 is a cross section view showing a section taken along line 32-32 of FIG. 30 thereof;
FIG. 33 is a top, front, left perspective view of a fourth alternative claimed configuration of the mug of FIGS. 1-8 showing our new design;
FIG. 34 is a front view thereof;
FIG. 35 is a rear view thereof;
FIG. 36 is a right side view thereof;
FIG. 37 is a left side view thereof;
FIG. 38 is a top view thereof;
FIG. 39 is a bottom view thereof; and,
FIG. 40 is a cross section view showing a section taken along line 40-40 of FIG. 38 thereof.
The contrast in shading shown in FIGS. 1-8 represents a contrast in appearance only and does not represent any particular color, material, texture or finish. The broken lines depicting the remainder of the mug show features that form no part of the claimed design.
